Primary Examiner—Doris V. Coles*Attorney, Agent, or Firm*—Dallett Hoopes[57] **CLAIM**

The ornamental design for a fish-mouth-gripping tool, as shown and described.

DESCRIPTION

FIG. 1 is a perspective view of a fish-mouth-gripping tool showing my new design;

FIG. 2 is a top plan view;

FIG. 3 is a front elevational view;

FIG. 4 is a rear elevation view;

FIG. 5 is a left side elevational view; and,

FIG. 6 is a bottom plan view.

The right side elevation is a mirror image of the left side elevation.

FIG. 1

FIG. 2

FIG. 3

FIG. 4

FIG. 5

FIG. 6
